W. S. Kline

Attorney

UNITED STATES PATENT OFFICE.

FRANK ANTONUCCIO, OF OAKLAND, CALIFORNIA.

BURNER.

Specification of Letters Patent. Patented Mar. 2, 1915.

1,130,132.

Application filed June 1, 1914. Serial No. 842,204.

To all whom it may concern:

Be it known that I, FRANK ANTONUCCIO, citizen of the United States, residing at Oakland, in the county of Alameda and State of California, have invented certain new and useful Improvements in Burners, of which the following is a specification.

The present invention relates to certain new and useful improvements in gaseous fuel burners, and more particularly to that type of burners which are designed for use in connection with water heaters, the object of the invention being to provide a device of this character which embodies novel features of construction whereby it can be readily taken apart and cleaned.

A further object of the invention is to provide a gaseous fuel burner which is comparatively simple and inexpensive in its construction, which will not become clogged by drippings, which can be quickly assembled or taken apart, and which will operate in an effective manner.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a top plan view of a gaseous fuel burner constructed in accordance with the invention. Fig. 2 is a vertical sectional view through the burner on the line 2—2 of Fig. 1. Fig. 3 is a plan view of the large burner ring, showing the same as detached from the burner. Fig. 4 is a side elevation of the same. Fig. 5 is a view similar to Fig. 3, showing the small burner ring. Fig. 6 is a plan view of the central burner plate. Fig. 7 is a plan view of a gaseous fuel burner, showing a modified form of the invention. Fig. 8 is a vertical sectional view on the line 8—8 of Fig. 7. Fig. 9 is a detached plan view of the outer burner ring used in the modified form of the invention. Fig. 10 is a side elevation of the same. Fig.

11 is a detached plan view of the inner burner ring used in the modified form of the invention. Fig. 12 is a plan view of the central burner plate used in the modified form of the invention.

Corresponding and like parts are referred

to in the following description and indicated in all the views of the drawings by the same reference characters.

Specifically describing the preferred embodiment of the invention, the numeral 1 designates a burner pan which has a shallow formation and is formed with an outwardly inclined peripheral side wall 2. A suitable feed pipe 3 communicates with the burner pan 1, said feed pipe being shown as provided with conventional air inlet openings 4 and a nipple 5 for connection with a gas pipe.

Arranged within the mouth of the burner pan 1 are two annular burner rings 6 and 7, together with a central burner plate 8, said members being formed with outwardly inclined side walls which coöperate with each other and the outwardly flared sides 2 of the pan to provide supporting means for holding the members in position. The burner ring 6 is formed with an outer peripheral flange 6^a and an inner peripheral flange 6^b, both of said flanges being flared outwardly and the outer flange 6^a resting against and engaging the sides 2 of the burner pan to support the ring 6 in position. In a similar manner the inner burner ring 7 is formed with an outer peripheral flange 7^a and an inner peripheral flange 7^b, both of which are inclined outwardly, the outer flange 7^a bearing against and engaging the inner flange 6^b of the ring 6 to support the burner ring 7 in position.

Arranged within the ring 7 is the central burner plate 8 which is formed with a peripheral upwardly projecting and outwardly inclined flange 8^a, said flange engaging the inner flange 7^b of the inner burner ring 7 to support the plate 8 in position. This central burner plate 8 is connected to the bottom of the pan 1 by means of some detachable fastening member such as the bolt 9. When this bolt is in position the two burner rings and central burner plate are held securely against displacement and the parts are held rigidly in an assembled position, although after the bolt has been removed, the various parts can be lifted out of position so as to be easily cleansed.

The outer inclined flange 6^a of the burner ring 6 is formed with a series of upright ribs 10 which fit within corresponding depressions 11 formed in the inclined sides 2 of the pan 1. It will also be observed that the outer faces of the ribs 10 are formed

with semicircular longitudinally disposed grooves 12 and that the bases of the depressions 11 are formed with corresponding longitudinally disposed semicircular grooves 13. These two sets of grooves 12 and 13 co-operate with each other to provide burner openings which lead from the pan 1 to the top of the burner. In a similar manner it will be observed that the outer flange 7^a of the smaller burner ring 7 is formed with ribs 14 adapted to be received within corresponding depressions 15 in the inner flange 6^b of the burner ring 6, the said ribs and depressions being provided with the corresponding grooves 16 and 17 respectively which co-operate with each other to provide burner openings. It will further be observed that the flange 8^a of the central plate 8 is formed with ribs 18 adapted to be received within corresponding depressions 19 in the inner flange 7^b of the burner ring 7, said ribs and depressions being formed with the corresponding grooves 20 and 21 which co-operate with each other to provide an inner annular series of burner openings. As indicated upon the drawings, the periphery of the larger burner ring 6 may also be provided at suitable intervals with positioning and supporting lugs 22 adapted to engage suitable seats 23 in the side walls 2 of the burner pan.

When the several burner rings and central plate are assembled within the mouth of the burner pan, the co-operating inclined walls of the members provide a supporting means for retaining them in position while the corresponding ribs and depressions bring about an interlocking connection between the members; the corresponding grooves providing a series of annular rows of burner openings. The members can be easily lifted out of position after the bolt 9 is removed, so that the burner can be easily and thoroughly cleansed at any time. It will also be observed that each of the rings 6 and 7 is constructed to provide an annular trough while the central burner plate 8 provides a pocket, the troughs and central pocket being adapted to catch and collect drippings from the boiler so that they will not find their way into the interior of the burner and interfere with the proper action thereof.

Figs. 7 to 12 inclusive of the drawing 55 serve to illustrate a modified form of the invention. The numeral 24 designates a burner pan which, as in the previous instance, is formed with a peripheral outwardly inclined side wall 25, and communicates with a fuel supply pipe 26. Arranged within the mouth of the pan are the concentric burner rings 27 and 28, together with the central burner plate 29. The outer burner ring 27 is formed with the outer peripheral flange 27^a and the inner peripheral

flange 27^b, the latter having only a fraction of the height of the former, although they are both outwardly inclined and the outer flange engages the inclined side wall 25 of the burner pan to support the ring in position. In a similar manner the inner burner ring 28 is formed with an outer peripheral flange 28^a and an inner peripheral flange 28^b, the latter being shorter than the former, and the outer flange 28^b engaging the inner flange 27^b of the ring 27 to support the ring in position. The central burner plate 29 is formed with a peripheral and outwardly inclined flange 29^a which engages the inner flange 28^b of the ring 28 to support the 80 plate 29 in position. The flanges 29^a, 28^a, and 27^a are of substantially the same height and are preferably higher than the flanges 27^b and 28^b, which are also of substantially the same height. It will also be observed 85 that the flanges 29^a, 28^a, and 27^a are provided on the outer faces thereof with the upwardly extending grooves 30 which co-operate with the walls or surfaces of the members against which they fit to provide 90 burner openings leading from the pan 24 to the top of the burner. As in the previous instance the burner rings provide troughs while the central burner plate provides a pocket for the purpose of collecting drippings and preventing them from passing 95 into the interior of the burner in such a manner as to interfere with the proper operation thereof. The upper edges of the flanges 29^a and 28^a overhang respectively the shorter flanges 28^b and 27^b so that drippings 100 will be prevented from leaking through the joints between the several members. A bolt or fastening member 31 may be provided for securing the central burner plate 29 to the bottom of the pan 24, and the periphery of the outer burner ring 27 may be provided as in the previous instance with supporting 105 and positioning lugs 32 adapted to engage corresponding seats 33 formed in the side 110 walls 25 of the pan.

Having thus described the invention, what I claim as new and desire to secure by Letters Patent, is:—

1. A burner including a pan having an outwardly inclined peripheral side wall, a plurality of concentric burner rings arranged within the mouth of the pan, and a burner plate within the inner ring, said burner rings being provided with outer and inner upstanding correspondingly inclined peripheral flanges and the burner plate being provided with an outer upstanding correspondingly inclined peripheral flange, the outer inclined faces of the outer flanges of the said rings and burner plate fitting 120 squarely against the correspondingly inclined outer faces of the inner flanges of adjacent rings and the wall of the pan to support the said rings and plate within the 125 130

mouth of the pan, the edges of said burner rings and plate being formed with grooves to provide burner openings.

2. A burner including a pan, a plurality of concentric burner rings arranged within the mouth of the pan, and a central burner plate within the inner ring, the outer and inner edges of the rings and edge of the burner plate being provided with grooves, 10 the grooves in the outer edges of the rings coöperating with the grooves of the inner edges of adjacent rings to provide burner openings.

3. A burner including a pan provided with an outwardly inclined peripheral side wall, a plurality of concentric burner rings arranged within the mouth of the pan and having outwardly inclined outer and inner flanges which coöperate with each other and 15 the inclined peripheral side wall of the pan to support the rings in position within the pan, and a central burner plate having an outwardly inclined edge which engages the flange of the inner ring to support the plate 20 and also provides a pocket for the collection 25 of drippings, the outer and inner edges of the rings and edge of the burner plate and inside edge of the peripheral wall of the pan being provided with grooves, the 30 grooves in the outer edges of the rings and burner plate coöperating with the grooves in the inner edges of the adjacent rings and wall of the pan to provide burner openings.

4. A burner including a pan, a plurality of concentric burner rings arranged within the mouth of the pan and formed at one edge thereof with upright ribs and at the opposite edge thereof with corresponding 35 depressions adapted to receive the ribs of adjacent rings, the said ribs and depressions being provided with corresponding 40 grooves forming burner openings, and a central burner plate within the inner ring.

5. A burner including a pan, a plurality of concentric burner rings having correspondingly inclined edges which coöperate with each other to support the rings in position within the pan, one of the edges of each burner ring being formed with upright 45 ribs and the opposite edge thereof with corresponding depressions adapted to receive 50

the ribs of an adjacent ring, the said ribs and depressions being provided with corresponding grooves forming burner openings, and a central burner plate arranged within 55 the inner ring.

6. A burner including a pan, a plurality of concentric burner rings arranged within the mouth of the pan and having side flanges so as to provide annular troughs for 60 the collection of drippings, and a central burner plate arranged within the inner ring, the side flanges of the burner rings and burner plate being correspondingly inclined 65 so as to coöperate with each other to support the members in position and one edge of each of the burner rings being formed with upright ribs while the opposite edge thereof is formed with corresponding depressions adapted to receive the ribs of an 70 adjacent ring, the said ribs and depressions having corresponding grooves coöperating with each other to provide burner openings.

7. A burner including a pan having outwardly inclined sides, a plurality of concentric burner rings arranged within the mouth of the pan and having outer and inner peripheral side flanges so as to provide annular troughs for the collection of drippings, 80 and a central burner plate arranged within the inner ring and provided with a peripheral flange providing a pocket for the collection of drippings, all of the flanges being inclined outwardly for coöperation with 85 each other and the inclined sides of the pan to support the members in position and the flange of the central burner plate as well as the outer flanges of the burner rings being formed with upright ribs while the inclined 90 sides of the pan and inner flanges of the burner rings are formed with corresponding depressions adapted to receive the ribs, said ribs and depressions having corresponding grooves therein which coöperate with each 95 other to provide burner openings.

In testimony whereof I affix my signature in presence of two witnesses.

FRANK ANTONUCCIO.
